The ornamental design for a locking security ring for pharmacy bottles, as shown and described.

DESCRIPTION

FIG. 1 is a top, front, perspective view of a locking security ring for pharmacy bottles showing our new design;

FIG. 2 is a bottom, rear, perspective view thereof;

FIG. 3 is a front view thereof, the rear view being a mirror image of the front view;

FIG. 4 is a right side view thereof, the left side view being a mirror image of the right side view;

FIG. 5 is a top view thereof; and

FIG. 6 is a bottom view thereof.

FIG. 7 is a top, front, perspective view of the locking security ring for pharmacy bottles of FIG. 1 shown in use with additional environmental subject matter;

FIG. 8 is a bottom, rear, perspective view thereof;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The features shown in broken lines are portions of the locking security ring for pharmacy bottles or environmental subject matter to the locking security ring for pharmacy bottles forming no part of the claimed design.
